LADDER BRACKET FOR SCAFFOLDS

Charles F. Hansen, Chicago, Ill.

Application November 12, 1946, Serial No. 709,188

5 Claims. (Cl. 248—238)

1

The present invention pertains to scaffold supports and more particularly to improvements in ladder jacks.

The primary object of the invention is to provide a scaffold support that is safe and reliable.

Another object is to provide a ladder jack having instrumentalities which preclude the possibility of becoming accidentally detached.

A further object of the invention is to provide a scaffold support of the ladder jack variety wherein a locking device is embodied which facilitates ready adjustment and assures the maintenance of such adjustment and thereby insures safety.

The invention features a locking device comprising a spring biased locking element which cooperates with a bayonet type slot to render a ladder jack readily detachable and demountable and still insure safety and security in its attached or mounted position.

A further feature of the invention resides in the flexibility of the scaffold support or ladder jack by giving to said support a four-point suspension on the ladder siderails, as well as a two-point suspension on the ladder rungs. The ladder jack according to the present invention is extensible and adjustable, within a predetermined range, to fit a ladder of any width and distance between rungs. Moreover, the strain and tension is taken up at a plurality of points and the risk of injury is reduced to a minimum. The scaffold support of the present invention will fit in any space between standards or side rails on a regular extension ladder. Also, the scaffold support can be used either as a bracket or as a hanger on outside or underside, respectively, of ladder.

Other objects and features of the invention will appear from the following description when taken in conjunction with the accompanying drawings, wherein,

Fig. 1 is a side elevation, partly in section, of the scaffold support or ladder jack according to the present invention;

Fig. 2 is a detail view of the pivotal connection of the arms of the ladder jack;

Fig. 3 is a perspective view of the spring-biased locking element of the invention in its operative position;

Fig. 4 is a top view of the locking element shown in Fig. 3;

Fig. 5 is a perspective view of the ladder jack arrangement of the invention mounted on a ladder in operative position;

Figs. 6, 7, and 8 are detail views of the upper anchor or suspension members, and

2

Figs. 9, 10, and 11 are detail views of the lower anchor or suspension members.

Having reference to Figs. 1 to 5 of the drawings wherein like reference characters indicate the same parts throughout the several views, a ladder 16 comprising side rails 12 and 13 and rungs 14 and 15, is illustrated in an inclined position in the manner of resting against a wall (not shown). Supported on the rungs 14 and 15 and braced by the standards or rails 12 and 13 is the ladder jack or scaffold support according to the invention.

The ladder jack, indicated generally as 16, comprises a horizontal member 17 adapted to be pivotally connected at 18 to a notched member or adjustor 19. Although the member 17 is shown in Fig. 1 as fashioned with an upwardly directed curved portion adapted to fit into the space provided by the member 19 and its reverted end 21 and pivotally constrained by rivet 18, every equivalent form of pivotal connection is, of course, contemplated.

Bar 19 is provided along its upper edge with a plurality of bayonet type slots 22 which are adapted to coact with a hasp-like member 23. Member 23 is provided with a pair of trunion supports 24 preferably integrally formed on said member 23. Trunnions 24 are adapted to be rotatably supported in a pair of brackets or clamps 30 secured to an upper anchor member, indicated generally as 26.

The member 17 has secured thereto by rivets 27 a trunnion portion 28 which is provided integrally therewith with a pair of trunnions 29 adapted to be rotatably supported by a pair of clamps 31 secured to a lower anchor member, indicated generally as 32. It is, of course, understood that the bar 17 and portion 28 may be made of one piece, such that the trunnions 29 are formed integral with the bar 17. Moreover, it is contemplated that the means of pivotally supporting the scaffold supporting members 23 and 28 to the anchor members 26 and 32 may take other well known forms.

Member 23 is provided with an elongated slot 33 of sufficient length 34 to freely admit the full width of bar 19. Interposed between the lower edge of bar 19 and the adjacent face of portion 23 is a locking element 35 pivotally mounted on portion 23 by means of a shouldered rivet 36 to permit free rotation of said locking element. Encircling the shoulder of rivet 36 and disposed between the locking element 35 and portion 23 is a coiled spring 37 one end of which grips 55 or embraces the edge of portion 23 and the other

end similarly embraces the proximate edge of locking element 35 whereby element 35 is normally biased in a counterclockwise direction, as viewed in Fig. 4, against a stop 37 fastened to member 23.

Locking element 35 is provided with a vertically directed flange 38 adapted to be locked under predetermined operating conditions, between stop 37 and bar 19. Instead of the stop 37, the locking element 35 may be provided with a depending flange 39 adapted to overhang and engage the member 23.

The upper anchor member 26 is shown in detail in Figs. 6, 7, and 8, and comprises a sheath 41 adapted to encase or surround a pair of extensible members 42 and 43 which are slidably retained in sheath 41 by bolts 44 and slots 45. The sheath 41 terminates along one of its bottom edges in conformations 46, 47, and 48. Conformations 46 and 48 encase the outside of the ladder rung 14 while the conformation engages the inside of rung 14. With this arrangement of conformations, the conformations 46 and 48 serve to sustain part of the load imposed on the scaffold plank 51 while the conformation 47 acts together with conformations 46 and 48 to retain the anchor member 26 upon the rung 14 against accidental displacement. The extensible members 42 and 43 are conformed with ends 52 adapted to wrap partly around the standards 12 and 13 of the ladder 11 to sustain the load imposed on scaffold 51.

The lower anchor member 32, shown in Figs. 9, 10, and 11 comprises a sheath 141 adapted to slidably accommodate extensible members 142 and 143 which are constrained to predetermined endwise movement by slots 145 and bolts 144. Sheath 141 is provided with conformations 146, 147, and 148 adapted to cooperate with rung 15 of ladder 11 so that the load on scaffold 51 is imparted through bar or member 17 to conformations 146 and 148. Conformation 147 acts together with conformation 146 and 148 to retain the anchor member 32 upon the rung 15 against accidental displacement.

The clamps 25 and 31 have not been shown in Figs. 6 to 11 because it is contemplated that the form of retainers and bearings for the trunnions 24 and 29 may be varied to include all equivalent forms. The member 19 may be made considerably longer and may contain a greater number of slots 22 to enhance its adjustment possibilities. Moreover, the clamps 25 may be so designed as to support the trunnions 24 closer to the upper edge of the anchor member 26 so that the member 19 may readily extend over the top edge of the anchor member. If this is not desired then the anchor member may be notched or slotted to permit passage of the member or bar 19 therethrough.

In the operation of the scaffold support according to the present invention, the anchor members 26 and 32 are placed upon the rungs 14 and 15, respectively, with the extensible members 42, 43, 142, and 143 properly adjusted to the width of the ladder and the conformations 52 and 152 embracing the standards 12 and 13. The locking element 35 is swung to the position indicated 35'' in Fig. 4, and the bar 19 is threaded through slot 33 to determine which notch 22 is to be engaged by members 23 so as to hold member 17 in a horizontal position which will properly support the scaffold planks 51. After this has been determined, the members 17, 19, and 23 are swung to the dotted positions 17', 19', and

23' shown in Fig. 1, whereat the flange 38 of locking element 35 will clear the bottom edge of member 19 and will be biased by spring 37 to the position against stop 37. With the element 35 in this position the bar 19 is locked against withdrawal because the restricted opening 55 of slot 33 is less than the width of the member 19. Now, when the ladder jack 16 is lowered to the solid line position shown in Fig. 1, the member 19 is locked against withdrawal, as shown in Fig. 3, and may be released only upon assumption of the abnormal position indicated by the dotted lines in Fig. 1 and manually swinging the locking element 35 to the dotted position 35'' indicated in Fig. 4.

In prior devices of the type herein shown there are not found the safety features of the present invention which overcome the dangers encountered by workers of the trade, and which dangers are recognized by framers of municipal and state codes for the safety and security of trade workers. With prior structures one may butt his shoulder against the lower member of the scaffold jack and pivot the scaffold jack upwardly to cause collapse and dislodgement of the scaffold, which eventuality is not possible with the structure according to the present invention.

Although the present invention has been described in connection with a specific embodiment thereof it is understood that all modifications are contemplated which come within the range and scope of the appended claims.

What is claimed is:

1. In a ladder bracket, a scaffold supporting member, anchoring means having rail straddling and rung straddling instrumentalities comprising facilities for pivotally supporting said member, suspension means pivotally articulated to said member and comprising a hasp element and an adjustor, said adjustor provided with notches cooperable with said hasp element, other anchoring means having rail straddling and rung straddling instrumentalities comprising facilities for pivotally supporting said hasp element, said hasp element provided with a slot adapted to freely receive said adjustor, and spring-loaded locking means pivotally carried on said hasp element effective cooperable with said notches under certain predetermined conditions to restrict said slot, whereby said hasp element and said adjustor are interlocked.

2. In a ladder bracket, a scaffold supporting member, anchoring means having rail straddling and rung straddling instrumentalities and comprising facilities for pivotally supporting said member, suspension means pivotally articulated to said member and comprising a first element having slot facilities and a second element having notch facilities, other anchoring means having rail straddling and rung straddling instrumentalities comprising facilities for pivotally supporting said first element, locking means pivotally carried on said first element and effective under certain predetermined operating conditions for restricting said slot facilities for interlocking said first element and said second element, and means associated with said locking means to prevent release of said locking means under said operating conditions.

3. In a ladder bracket, a scaffold supporting member, anchoring means having rail straddling and rung straddling instrumentalities comprising facilities for pivotally supporting said member, means pivotally articulated to said member

and comprising a hasp element and an adjustor, said adjustor threadable through a slot in said hasp element and provided with notches cooperable with said hasp element, other anchoring means having rail straddling and rung straddling instrumentalities comprising facilities for pivotally supporting said hasp element, a slot restricting instrumentality pivotally mounted on said hasp portion, said slot restricting instrumentality adapted to partially cover said slotted opening in said hasp to prevent, within predetermined limits, detachment of said hasp portion and said adjustor, a stop on said hasp element for limiting rotation of said instrumentality, and a flange integral with said instrumentality interposable between said stop and said adjustor for locking said instrumentality against rotation within said predetermined limits.

4. In a ladder bracket, a scaffold supporting member, anchoring means comprising facilities for pivotally supporting said member, means pivotally articulated to said member and comprising a hasp element and an adjustor, said adjustor threadable through a slotted opening in said hasp element and provided with notches cooperable with said hasp element, other anchoring means comprising facilities for pivotally supporting said hasp element, and an instrumentality pivotally mounted on said hasp element and adapted to partially cover said slotted opening in said hasp, whereby said hasp element when resting in one of said notches is prevented, under certain operating conditions, from becoming detached from said adjustor.

5. In a ladder bracket, a scaffold supporting member, anchoring means comprising facilities

for pivotally supporting said member, means pivotally articulated to said member and comprising a hasp element and an adjustor, said adjustor threadable through a slot in said hasp element and provided with notches cooperable with said hasp element, other anchoring means comprising facilities for pivotally supporting said hasp element, a slot restricting instrumentality pivotally mounted on said hasp element, said instrumentality cooperable with said notches to prevent, within predetermined limits, detachment of said hasp portion and said adjustor, a stop on said hasp element for limiting rotation of said instrumentality and a flange integral with said instrumentality interposable between said stop and said adjustor for locking said instrumentality against rotation within said predetermined limits.
